UNITED STATES PATENT OFFICE.

EDGAR J. SICK, OF DUSHORE, PENNSYLVANIA.

FOUNTAIN-BRUSH.

992,074.

Specification of Letters Patent.

Patented May 9, 1911.

Application filed August 30, 1910. Serial No. 579,677.

To all whom it may concern:

Be it known that I, EDGAR J. SICK, a citizen of the United States, residing at Du-
5 shore, in the county of Sullivan and State
of Pennsylvania, have invented new and
useful Improvements in Fountain-Brushes,
of which the following is a specification.

This invention relates to fountain brushes
and more particularly to fountain blacken-
10 ing brushes, the object being to provide a
blackening brush which will have means to
feed a blackening fluid to the bristles there-
of so that it may be readily applied to the
shoes without soiling the hands and in an
15 economical manner.

A further object of the invention is the
provision of a fountain brush of this type
which will have a plurality of distributing
20 nozzles all open to the supply tank and a
valve for simultaneously controlling all of
the ports to the discharge nozzle.

Further objects of the invention will appear
as the following specific description is
25 read in connection with the accompanying
drawing which forms a part of this applica-
tion, and in which:

Figure 1 is a side elevation. Fig. 2 is a
longitudinal sectional view.

Referring more particularly to the draw-
30 ing 1 represents the back of the brush and 2
the bristles thereof which are separated at
suitable points to permit the passage of the
discharge nipples 3 which communicate with
35 the supply tank 4 secured in any suitable
manner upon the back. A yoke-shaped
handle 5 is provided and the tank has a
supply opening closed by a screw cap 6.

Suitable packing cylinders 7 extend up
40 from each end of the tank immediately be-
low the handle 5 and have passing therethrough
the yoke-shaped valve operating lever 8. This lever is connected through

links 9 to the eyes 10 which are mounted on
opposite ends of the valve 11. A packing
12 is secured upon the bottom of the valve
and a spring 13 holds the valve and the
packing over the ports leading to the dis-
charge nozzles. By pulling up on the yoke-
shaped lever 8, the valve is lifted off of all
of the ports simultaneously so that each 50
portion of the brush is fed with a suitable
quantity of the blackening fluid at the same
time. The valve practically fits the inter-
ior of the cylinder as shown so as to pre-
vent wabbling when the spring 13 is cen- 55
trally mounted.

Having thus described the invention, what
is claimed is—

A fountain brush comprising a brush back
having bristles secured thereto and a plu- 60
rality of apertures passing through the same,
of a supply tank secured to the back, noz-
zles carried by the tank, and projecting
through the apertures in the back, a yoke
shaped manipulating handle carried by the 65
tank, a valve plate mounted in and substan-
tially fitted to the interior of the tank, a
central spring wedge between the tank and
valve plate for normally holding the same
in position to close the nozzles, a yoke 70
shaped lever arranged beneath and lying
parallel with the handle and pivotally con-
nected to opposite sides of the valve plate
for bodily raising the same whereby all of
the parts are simultaneously uncovered, and 75
packing glands secured to the tank for re-
ceiving the separate legs of the lever.

In testimony whereof I affix my signature
in presence of two witnesses.

EDGAR J. SICK.
